Attorney

UNITED STATES PATENT OFFICE.

RAY O. DURST, OF BRADFORD, OHIO.

GRATE ATTACHMENT FOR STOVES AND FURNACES.

Application filed October 5, 1921. Serial No. 505,504.

To all whom it may concern:

Be it known that I, RAY O. DURST, a citizen of the United States, residing at Bradford, in the county of Miami and State 5 of Ohio, have invented certain new and useful Improvements in Grate Attachments for Stoves and Furnaces, of which the following is a specification.

The present invention consists of a grate 10 attachment for stoves and furnaces.

It is well known in the art to provide air tight stoves which are especially adapted for use in railway cabin cars, etc., where the stove is, of necessity, subjected to constant 15 vibration, periodical air blasts etc., thereby minimizing possibility of the hot coals, ashes etc. being projected from the stove to the floor. However, in these types of stoves now in use it is necessary to open the 20 ash door in order to shake the grate with the result that sparks are emitted from the grate as is also coal gas, dust, etc., which prove very offensive, if not injurious, to the attendant. It is the principal object of this 25 invention therefore, to provide a grate and associate mechanism which will permit the grate to be shaken without the necessity of opening the ash door or otherwise venting the stove.

Another object of the invention is to provide means for locking the grate from movement thereby preventing accidental shaking of the grate by the swinging movement of a railway car or other vehicle in which it 35 is carried.

The above and other objects of this invention will be in part described and in part understood from the following description of the present preferred embodiment of 40 the invention taken in connection with the accompanying drawings wherein:—

Fig. 1 is a fragmentary front elevational view partly in section of a stove embodying my improvement.

Fig. 2 is a horizontal sectional view of the stove base showing a grate constructed in accordance with this invention and the shaker means attached thereto, the said shaker attachment being shown in a closed 50 position.

Fig. 3 is a similar view showing the shaker attachment in an open position; and

Fig. 4 is a detail fragmentary elevational view of the stove base showing to advantage 55 the shaker locking mechanism.

In the drawings a portion of an air-tight

or hot blast stove 5 is shown the body and base of which may be of standard construction. The base 6 of the stove is equipped with an ash door 7 covering an opening 60 through which the ash pan may be removed in the usual way.

In this type of stove, a rotary grate such as that shown at 8 in Fig. 2 is provided. When constructed in accordance with this 65 invention the grate has an arm 9 extended from its periphery and terminating short of the ash door 7. The outer end of said arm is provided with an elongated slot 10 which receives one end of a shaker rod 11. 70 The opposite end of the rod extends through an opening in one side of the stove base 6 and has a handle 12 formed on its extremity. As is apparent reciprocation of the rod 11 will cause the grate to be rotated 75 in an obvious manner and for an obvious purpose. By providing the elongated slot 10 ample play of the rod 11 will be permitted so as to insure free movement of the 80 grate without possibility of binding.

In order to prevent accidental movement of the grate suitable locking means is provided. This means consists of a collar 13 formed on the rod 11 in proximity to the handle 12. The collar is adapted to rest in 85 a complementary recess 14 formed in the side of the base 6. A locking tumbler 15 is pivotally mounted upon the base 6 in proximity to the recess 14. Normally, the tumbler will 90 gravitate into engagement between the handle 12 and collar 13 thereby preventing movement of the rod 11.

In use of this device when it is desired to shake the grate the tumbler 15 is elevated 95 so as to permit withdrawal of the collar 13 from the recess 14. After this has been done the tumbler may be permitted to gravitate into engagement with the rod 11 and the latter reciprocated by the handle 12, in an apparent manner. The grate is relocked 100 by simply urging the handle 12 inwardly and disengaging the tumbler 15 until the collar 13 seats in the recess 14 following which the tumbler is permitted to gravitate 105 into reengagement between the handle 12 and collar 13.

The above described device will eliminate the necessity of opening the ash door or in any way venting the stove when the grate is to be shaken at the same time permitting the grate to be thoroughly agitated 110 in the usual way. The device is simple and

may be applied to standard types of stoves without appreciable cost.

Various changes may be made in this device especially in the details of construction, proportion and arrangement of parts within the scope of the appended claim.

What is claimed is:—

In combination with a stove a portion of the body of which is depressed and provided with a slot, a grate mounted in the stove and equipped with an arm concealed completely within the latter, a rod arranged through the slot in said stove body and

engaged with said grate arm, a collar formed on said rod and engageable in the depression of the stove body, a locking plate mounted on the stove body and movable across the depression of the latter to prevent disengagement of the collar therefrom.

In testimony whereof I affix my signature in presence of two witnesses.

RAY O. DURST.
